PHOTOGRAPHIC VIEWER

Robert E. Cherouvrier, Paris, France

Application January 11, 1955, Serial No. 33,918

Term of patent 7 years

(Cl. D61—1)

The single figure is a front perspective view of the photographic viewer taken from above, showing my new design.

The rear of the viewer is plain and the side not shown is the same as the side shown. The dominant feature of my design resides in the portions shown in full lines.

I claim:

The ornamental design for a photographic viewer, as shown and described.
